UNITED STATES PATENT OFFICE.

STACY B. HASELTINE, OF CHICAGO, ILLINOIS, ASSIGNOR TO W. H. MINER, OF CHICAGO, ILLINOIS.

DRAFT-YOKE FOR RAILWAY-CAR DRAFT-RIGGING.

1,120,194.

Specification of Letters Patent.

Patented Dec. 8, 1914.

Application filed August 11, 1913. Serial No. 784,036.

To all whom it may concern:

Be it known that I, STACY B. HASELTINE, a citizen of the United States, residing at Chicago, in the county of Cook and State of Illinois, have invented a certain new and useful Improvement in Draft-Yokes for Railway-Car Draft-Rigging, of which the following is a full, clear, concise, and exact description, reference being had to the accompanying drawings, forming a part of this specification.

My invention relates to draft yokes for railway car draft rigging.

The object of my invention is to provide a draft yoke in which a secure connection between the yoke and draw bar is afforded, and in which the draw bar is readily removable from the yoke.

In the drawings forming a part of this specification—Figure 1 is a perspective view of a portion of a draw bar and of a draft yoke embodying my invention; Fig. 2 is a vertical longitudinal sectional view partly broken out; Fig. 3 is a detail of a portion 25 of the detachable limb of the yoke; Fig. 4 is a detail view showing the key in perspective view; Fig. 5 is a perspective view of the connecting thimble; Fig. 6 is a cross section taken on line 6—6 of Fig. 2; Fig. 7 is a 30 vertical longitudinal section view partly broken away illustrating a modification; Fig. 8 is a perspective view of said modification.

Referring to the drawings the numeral 9 35 represents a draw bar, the rearward portion thereof only being shown in the drawings, said draw bar being of standard form, having rivet holes 10, 10 vertically disposed through the butt 11 thereof and the upper 40 and lower shoulders 12 and 13 respectively.

The draft yoke comprises an upper limb 14, a lower detachable limb 15, and a connecting thimble 16. The upper limb 14 is forwardly provided with a transverse inwardly projecting lugs 18, 18 adapted to enter the rivet holes 10, 10 in the face of the draw bar adjacent thereto. The said 45 upper limb 14 is provided with preferably integral downwardly extended lateral plates 19, 19 joined together at their bottom ends by the plate 20, and forming with the upper limb the walls of a hollow head with- 50 in which the draw bar is received. The

lower plate 20 is upwardly and rearwardly tapered on its inner face 21 to conform to the adjacent tapered face 22 of the key 23. The rear end of said upper limb 14 is provided with a transverse member 24, which in preferable construction has an outward bend 25 therein, and is preferably with the rear end of the upper limb provided with the reinforcing flanges 26, 26.

The detachable limb 15 is adapted at its forward end to enter the hollow head hereinbefore described, and is provided with means to engage the lower face of the draw bar 9. At its forward end the detachable limb 15 is provided with a transverse inwardly turned gib 27, which is adapted to engage against the shoulder 13 of the draw bar, and is also provided on its inner face with the lugs 28, 28, which are adapted to enter the holes 10, 10 in the adjacent face of the draw bar.

At a point substantially immediately back of the rear edge 29 of the lower wall 20 forming the yoke head the detachable limb 15 is provided with a depending flange 30 having a perforation 31 therethrough for the passage of the bolt 32, which is received in the key 23 through the longitudinal perforation 33 therein, the said bolt being provided at its rear end with a head 34, and at its forward end is suitably threaded to receive the nut 35. The said key 23 is adapted to enter the hollow head between the detachable limb and the lower wall 20 of said head, and by means of the said bolt 32 may be drawn rearwardly in said head, wedging the limb of the yoke into secure engagement with the draw bar. At its rear end the detachable limb is provided with transverse flanges 36, 36, forming substantially a T-head thereon, the rear faces 37, 37 of said flanges engaging against the forward face 38 of the lower portion of the transverse member 24 of the upper limb 14, and the forward face 39 of the flanges 36, 36 being substantially parallel and in the same plane with the forward face 40 of the upper portion of the transverse member 24 of the limb 14.

A perforation 41 in one of the flanges 36 registering with a perforation 42 in the transverse member 24 of the limb 14 is adapted to receive a bolt 43, which is provided at its rear end with a head 44; and is suitably threaded at its forward end to

receive the nut 45, by means of which bolt the rear end of the detachable limb 15 is secured to the transverse member 24.

The thimble 16 is preferably a hollow box-like member, and preferably rectangular in cross section. The upper and lower limbs of the yoke are each provided on their inner faces with means for engaging the said thimble, preferably comprising the lugs 46, 47, adapted to enter the open ends 47, 47 of the said thimble. The said lugs conform in shape to the openings in the ends of the thimble, and in preferable construction are integral with the limbs of the yoke.

To remove the draw bar from the yoke the bolt 32 is driven rearwardly out of the key 23 and the flange 30 with which the detachable limb 15 is provided, and the key 23 removed from the hollow head. The bolt 43 is removed from the rear end of the yoke, whereupon the detachable limb is dropped within the head and at its rear end, dropping the draw bar and disengaging the upper shoulder 12 thereof from the gib 17, and disengaging the lugs 18 from the rivet holes 10, 10 in the draw bar, whereupon the draw bar may be disengaged from the detachable limb and removed forwardly from the yoke. That the thimble 16 and draft rigging springs and followers may be removed upon the separation of the limbs of the yoke will be obvious.

In the modification illustrated in Figs. 7 and 8 the numeral 48 represents a draw bar, 35 49 the butt thereof, 50 the draft yoke comprising an upper limb 51, a lower limb 52 and a connecting thimble 53. The upper limb 51 is forwardly provided with a transverse inturned gib 54 adapted to engage one 40 of the shoulders 55 of the draw bar, and is also provided at its forward end with depending plates 56, 56, forming with the lower plate 57 a hollow head 58 to receive the draw bar. The lower plate 57 is tapered 45 on its inner face 59 to receive the taper key 60, which is employed to secure the detachable limb 52 within the head and in engagement with the draw bar.

The upper limb 51 is provided with a 50 downwardly extended flange 61 adapted to meet an upwardly extended flange 62 with which the lower limb 52 is provided, forming a wall at the rear face 63 of the coupler butt. The upper limb is also provided with 55 a preferably integral downwardly extended thimble 64, preferably hollow at its lower end to receive the upwardly extending lug 65 with which the lower limb 52 is provided. At its rear end the upper limb 51 60 is provided with a transverse downwardly turned member 66, having in preferable construction the integral reinforcing flanges 67, 67 which extend downwardly beyond the lower end 68 of the said transverse member, forming between them a slot 69 within

which the rear end of the lower detachable limb 52 is received.

At its rear end the lower limb 52 of the yoke is provided with an upturned transverse flange 70 adapted to engage the rear face 71 of the transverse member 66 of the upper limb of the yoke, the said lower limb 52 being held in engagement with the upper limb at the rear end by means of the bolt 72 passing through the lower ends of the flanges 67, 67 and the preferably integral flanges 79, 79 provided at the rear of the detachable limb. The bolt 72 is thus in double shear.

At its forward end the detachable limb 52 is provided with an inturned gib 73 adapted to engage the adjacent shoulder 74 of the draw bar, and immediately back of the hollow head of the upper limb is provided with a depending flange 75 adapted to engage the rear edge 76 of the member 57 of the hollow head, which said flange is provided with a perforation 77 to receive the bolt 78 which passes through the key 60, and is adapted to be employed in drawing the taper key 60 into position and securing the same within the hollow head.

To remove the draw bar the bolt 72 is removed, the bolt 78 withdrawn from the taper key 60, which may then be removed, dropping the detachable arm 52, whereupon the draw bar may be forwardly withdrawn from the yoke or the draft rigging dropped.

I claim:

1. The combination with a draft yoke 100 having a detachable limb, of a hollow connecting thimble, the limbs of the yoke being provided with lugs adapted to enter the thimble to secure the same between said limbs.

2. The combination of a draft yoke having a detachable limb with a connecting thimble, the limbs of the yoke being provided with means for engaging said thimble between them, said thimble being disengaged through the removal of the detachable limb.

3. The combination with a draft yoke having a detachable limb, of a hollow connecting thimble, each limb of the yoke being provided with an inwardly turned lug adapted to enter the ends of said thimble and to hold said thimble between the limbs of the yoke, the said lugs being removable from the thimble only on the disengagement of the detachable limb.

4. In a draft rigging for railway cars, the combination with a standard draw bar having rivet holes therethrough, with a draft yoke comprising a limb having a hollow head and a detachable limb connected thereto and entering the hollow head, the said hollow head being adapted to receive the draw bar, and each of said limbs being provided with inwardly projecting lugs

adapted to engage within the rivet holes in said draw bar.

5. In a draft rigging for railway cars, in combination, a standard draw bar having 5 rivet holes, a draft yoke comprising a limb having a hollow head and a detachable limb, and means to secure said detachable limb within the hollow head at its one end and to the first mentioned limb at its other 10 end, each of said limbs being provided with inturned gibs to engage the draw bar, and with inwardly projecting lugs to engage within the rivet holes of the draw bar.
6. In a draft rigging for railway cars, in 15 combination, a draw bar, a draft yoke comprising a limb having a hollow head to receive the draw bar, and a detachable limb adapted to enter said head and engage the
- draw bar, the detachable limb being provided at its rear end with a transverse flange 20 and a bolt to connect said flange to the first mentioned limb.
7. In a draft rigging for railway cars, in combination, a draw bar, a draft yoke comprising a limb having a hollow head to receive the draw bar, and a detachable limb adapted to enter said head and engage the draw bar, the detachable limb being provided at its rear end with a transverse flange extending below said limb, and a bolt 25 30 to connect said flange to the first mentioned limb.
